UNITED STATES PATENT OFFICE

HANS J. ASLESON, OF MINNEAPOLIS, MINNESOTA

TRUSSED METAL STRUCTURE

Application filed July 8, 1929. Serial No. 378,815.

My present invention relates to trussed steel or metal structures and relates particularly to improved means for connecting the diagonals or lacings to the longitudinal members of such trussed structures. The term "truss structure" is herein used in a broad sense to include structures usually specifically designated as building trusses, bridge trusses, trussed girders and beams and trussed columns. In all these structures the invention relates particularly to the improved means for connecting the lacings or diagonal members with the longitudinal members.

It is a known fact that joints formed between truss-forming members and especially welded joints are not as strong in tension as they are in shear or compression. In accordance with my invention, the diagonals of the truss are bent in zig-zag form and are provided at their apices with slots that adapt them to receive and embrace flanges of the longitudinal members. When the diagonals are thus applied to and lapped with the flanges of the longitudinal members, they are welded together at the lapped joints either electrically or by the use of a torch and the accumulated metal of the welds are applied in such manner as to resist separation in shear. This gives the strongest kind of connection at the joints.

In the accompanying drawings, which illustrate the invention as applied to a truss of the type generally designated as a building truss and which is especially designed for use in garages or the like, like characters indicate like parts throughout the several views.

Referring to the drawings:

Fig. 1 is a view showing the truss in side elevation and the parts of the building in vertical section;

Fig. 2 is a transverse vertical section taken on the line 2-2 of Fig. 1;

Fig. 3 is a fragmentary view showing a portion of the zig-zag diagonal before it has been bent into zig-zag form but after the slot has been punched therein to form a joint lap;

Fig. 4 is a view in elevation showing one of the struts used in the truss illustrated;

Fig. 5 is a fragmentary side elevation on a larger scale than in Fig. 1 illustrating a struc-

ture in which the zig-zag diagonal is formed from an angle iron; and

Fig. 6 is a section taken on the line 6-6 of Fig. 5.

Referring first to the construction illustrated in Figs. 1 to 4, inclusive, the numerals 7 and 8 indicate, respectively, the top and bottom longitudinal members of the truss, both of which as shown in this structure are formed from T-beams with their flanges turned inward and welded together at 9. The separated intermediate portions of the longitudinal members 8 and 9 are trussed by a diagonal-forming member 10 that is bent zig-zag or with alternated V-shaped bends and projecting apices 11 that have slots 12 adapting the apices thereof to receive and embrace the inturned flanges of said members 7 and 8. In the structure shown in Figs. 1 to 4, the diagonal-forming member 10 is formed from a normally flat steel bar and the slots 12 will preferably be punched therein before the member is bent into zig-zag form. The lapped points of the several joints are then very firmly connected by accumulated steel welded thereto as indicated at 13. This welded material 13 it will be noted, is applied at the joints where it is located on the inner sides of the angles 11 and so that they will resist in shear separation of the joints.

Wherever it is feasible, the entire diagonal member of the truss will be made of one piece bent into a zig-zag form stated, but in some cases the diagonal member can be made up of a plurality of members connected by welding or otherwise. The truss also preferably is provided with struts 14 which, in the structure illustrated in Figs. 1 to 4, inclusive, are formed from flat steel bars provided at their ends with notches 15 that embrace the inturned flanges of the members 7 and 8 and are connected thereto by welding.

Where stiffest kind of diagonal member is desired, it can be made from angle bars 10^a bent into zig-zag form and provided at its angles with slots 12^a that embrace the flanges of the members 7 and 8. In bending the angle iron, it will naturally be flattened out at its apices as indicated at 11^a. When

these flattened and slotted angle portions are caused to straddle and embrace the inturned flanges of the members 7 and 8, the welding material will be preferably applied to the inner side of the angles, thereby producing a very strong truss. The truss described has the further advantage that it may be cheaply produced both in the formation of its individual elements and in the assembly thereof. From what has been said, it will be understood that the invention is capable of modification within the scope of the invention broadly disclosed and claimed and that it is capable of wide application and general utility in trussed metal structures.

What I claim is:

1. A trussed metallic structure comprising longitudinal members and a diagonal reinforcing member, the latter being formed with 20 reversely bent angles and slotted at its apices to lap with portions of said longitudinal members and the interlapped portions of said angles being connected by metal applied to resist separation in shear, the said diagonal members being formed from an angle bar material spread out or flattened at its apices where it embraces portions of said longitudinal members.

2. A trussed metallic structure comprising 30 longitudinal members and a diagonal reinforcing member, the latter being formed with reversely bent angles and slotted at its apices to lap with portions of said longitudinal members and the interlapped portions of said 35 angles being connected by metal applied to resist separation in shear, said longitudinal members having inturned flanges and said lacing being formed from angle bar material flattened at its slotted apices where it embraces the flanges of said longitudinal members.

3. A fabricated steel structure comprising a longitudinal member, and a diagonal member, the latter being formed with a reversely 45 bent slotted angle interlapping with a portion of said longitudinal member, the interlapping portions of said two members being connected by metal welded thereto and arranged to resist separation in shear.

50 4. A trussed metallic structure comprising longitudinal members and diagonal reinforcing members, the latter being formed with reversely bent angles the apices of which are longitudinally slotted between their side 55 edges to lap with portions of said longitudinal members, said lapped portions being connected by metal applied to resist separation in shear.

5. The structure defined in claim 4 in further combination with metallic struts applied between said longitudinal members in line with certain of the apices of said reinforcing member.

6. A trussed metallic structure comprising flanged longitudinal members and a diagonal

reinforcing member, the latter being formed with reversely bent angles, the apices of which are longitudinally slotted between their side edges to lap with flanges of said longitudinal members, the interlapped portions of said members being connected by metal welded thereto and arranged to resist separation in shear.

7. The structure defined in claim 6 in further combination with metallic struts lapped with and welded to said longitudinal members and to the apices of the angles of said reinforcing member.

In testimony whereof I affix my signature.

HANS J. ASLESON.
